HORN SUPPORT

Application filed December 19, 1929. Serial No. 415,213.

This invention relates to horn supports and more particularly to horn towers for use in sound picture installations.

The principal object of the invention is 5 the provision of a simple and inexpensive support for holding a horn in an adjusted position.

One embodiment of the invention contemplates a movable tower having a rotatable 10 frame for suspending a sound picture horn therefrom and provided with mechanisms for tilting and rotating the horn with respect to the tower.

It is believed that a complete understanding 15 of the invention may be had from the following detailed description when taken in conjunction with the accompanying drawings, wherein

Fig. 1 is a perspective view of a horn tower 20 embodying the invention;

Fig. 2 is a fragmentary perspective view of a modified support for the horn, and

Fig. 3 is a fragmentary perspective showing another modified support for the horn.

25 Referring now to the drawings wherein like reference numerals indicate similar parts throughout the several views, the numeral 10 designates generally a portable horn tower comprising a plurality of uprights 11—11 interconnected by a plurality of crossbars 12—12 to form a rectangular frame work on which is fastened a ladder 13. The lower ends of the uprights are provided with rollers or casters 14—14 to permit the tower to be 30 moved readily to various locations on a stage, for example, to obtain the best acoustical effect in a theater.

Across the top of the tower are secured two parallel channels 17—17 on which is mounted 40 medially of the ends thereof a bearing plate 18. As shown in Fig. 1, a rotatable frame 19 is suspended from a bolt 20 journaled in the bearing plate 18. The frame 19 is of triangular shape and carries at its base or forward end chains or ropes 21—21 for suspending the large end of a horn 22 therefrom. The rear end of the horn is adjustably suspended by means of a chain or rope 23 secured to a bracket 24 on the horn and passing over 45 a pulley 25 fastened on the apex of the frame

and thence through a guide eyelet 26 on the horn to a tie-bar 27 of the tower. Also secured to the apex or rear end of the frame 19 are two ropes 30—30 one passing over a pulley 31 on an upper crossbar 12 on one side of the frame, and the other passing over a pulley 32 positioned on a crossbar on the opposite side of the frame and both of the ropes passing from the pulleys to the tie-bar 27. 55

In the use of the horn support with sound picture productions the tower is moved on the stage to a desired location adjacent the screen on which the picture is projected. The horn is then rotated clockwise or counter-clockwise by the use of the ropes 30—30 and moved in a vertical plane by means of the pulley 25 and the rope 23 to properly position the horn according to the acoustics of the theater to obtain the best sound effect. 60

Fig. 2 is illustrated a modified horn support consisting of a wheel-shaped member 35 which has an upwardly extending shaft portion 36 which is journaled in the bearing plate 18 and which has a worm-wheel 37 mounted thereon so as to mesh with a worm 75 38. The worm 38 is manually rotated by a shaft 39 which, as seen from the front of the tower, is journaled in a bearing 40 secured to the right-hand channel 17 and in a bearing 41 mounted on the upper right-hand 80 crossbar 12. The bearing 41 is provided with a dial 42 upon which the angular position of the horn with respect to the tower may be indicated by a pointer 43 mounted on the shaft 39. The horn is suspended from the 85 wheel-shaped member 35 by ropes 21—21 and 23 in a manner similar to that previously described for the structure shown in Fig. 1. By turning a crank 44 on the shaft 39 the horn may be rotated through a predetermined 90 angle and by moving the rope 23 the horn may be tilted.

Another modification of the horn support is shown in Fig. 3 wherein the horn is suspended from the triangular frame 19 as has been previously described for the embodiment of the invention shown in Fig. 1, with this distinction that the bolt 20 is replaced by another bolt 45 having a horizontal opening 95 46 through which a rod 47 is free to slide. 100

Near the outer end of this rod is located a headed pin 48 free to move up and down in a slot in the rod so that upon the rod being moved to set the horn in a given position, the rod may be brought into alignment with the nearest of a series of apertures 49 in the upper right-hand crossbar 12 and the pin 48 dropped into the aperture, thus to locate the horn in a predetermined position.

10. What is claimed is:

1. A horn support comprising a tower, means comprising a non-rigid material for supporting a horn within the tower, means for maintaining the supporting means in a predetermined position, and means for moving the horn vertically with respect to the supporting means.

2. A horn support comprising a tower, means for suspending a horn therein through the agency of non-rigid material, means for adjusting the position of the horn vertically and horizontally, and means for maintaining the horn in an adjusted position.

3. A horn support comprising a portable tower, a rotatable frame within the tower, means for adjustably suspending a horn from the frame through the agency of non-rigid material, means for rotating the frame, and means for retaining the frame in predetermined adjusted positions.

4. A horn support comprising a portable tower, a rotatable frame within the tower, means for suspending the mouth end of a horn from the frame, means for adjustably suspending the other end of the horn from the frame to permit tilting of the horn, and means for rotating the frame to adjust the position of the horn.

5. A sound picture horn support comprising a movable tower, a rotatable frame mounted in the tower, means for suspending the large end of a sound picture horn from one portion of the frame, adjustable means for suspending the small end of the horn in a tilted position, and means for rotating and securing the frame in a predetermined position relative to the tower.

6. A horn support comprising a movable tower, a triangular frame within the tower, means for suspending one end of a horn from the base of the triangular frame, means for adjustably suspending the other end of the horn from the apex of the frame to permit tilting of the horn, means for rotating the frame, and means for retaining the frame in a predetermined adjusted position.

Signed at New York, N. Y., this 26th day of November, 1929.

ROBERT L. SARBACHER.
